UNITED STATES PATENT OFFICE.

CHARLES B. PECK, OF SUFFERN, NEW YORK.

WASHING PAPER.

Application filed March 26, 1926. Serial No. 97,673.

So called soap sheets for washing have been made by coating tissue paper with soap. These, however, when wet, quickly roll up into wads and are ineffective. Other soft 5 papers disintegrate when rubbed and leave unpleasant fuzz on the hands. Stiff papers can not be used to rub the hands. It has also been proposed to use soap coated woven fabrics as a scrubbing medium, but these are 10 too expensive.

The main object is to provide a cheap and convenient soaped sheet satisfactory for scrubbing the hands and face.

Another object is to provide a useful advertising medium.

The drawing shows a perspective view of one form of sheet embodying my invention. The shape of the sheet, however, is immaterial. It should be large enough, however, to 20 permit its use like a wash cloth. 4" x 5" is a convenient size.

I use a paper which is comparatively thin and quite flexible when wet and which is tough and not subject to surface disintegration when rubbed vigorously. A paper 25 weighing about .01 lb. per sq. ft. is suitable if made of the proper stock. I have found a paper made from rag stock is a suitable base although it may contain a small percentage of sulphate pulp. This paper is treated in a bath of acid and then washed. Sulphuric acid is preferred but nitric acid may be used with it or alone. This leaves the paper absorbent and very tough when 30 wet. A suitable commercial paper is known sometimes as vegetable parchment.

The paper web or sheet is treated with the soap, preferably in a hot solution form, so as to lightly coat both sides and impregnate

the paper. The paper can be coated by running it through a bath, or coated by a brush, or the soap may be applied by rolls or by spraying.

Abrasive material such as pumice, talc, sand, etc. may be mixed with the soap or applied after the paper is coated and rolled in. Cleaning medium such as almond or corn meal may also be mixed with the soap or applied afterwards.

Advertisements may be printed or embossed on or in the paper and the sheets may be given away by hotels or other concerns. The soap may be printed or applied in colors and in different designs if desired.

Sheets prepared in this way are very effective and pleasant to use. They do not tear, wad up or rub off and in fact may be used more than once as the soap dissolves out rather slowly.

I claim:

1. As an article of manufacture, a washing sheet comprising a thin vegetable parchment vehicle weighing approximately one hundredth of a pound per square foot impregnated with soap.

2. A washing sheet comprising a thin vegetable parchment paper vehicle having the characteristic of flexibility when wet and sufficiently tough and tenacious to prevent tearing or surface disintegration when used 70 for scrubbing, said vehicle being impregnated with soap.

3. A washing sheet comprising a thin paper foundation composed principally of acid-free, parchmentized rag stock impregnated with soap.

CHARLES B. PECK.
